UNITED STATES PATENT OFFICE.

OSCAR VENDAL NELSON, OF RACINE, WISCONSIN.

WINDOW-SCREEN FRAME.

Application filed November 26, 1926. Serial No. 150,917.

The present invention relates to a screen sash formed of all metal parts including side rails, each of which is formed from a single sheet of metal and a plurality of clip strips, each of which is formed from a single sheet of metal for holding the screen foraminous sheet in engagement with the rails.

Another important object of the invention lies in the formation of a screen sash of this nature which will be of a strong and durable rigid structure comparatively inexpensive to manufacture, and thoroughly efficient and reliable in use.

With the above and numerous other objects in view as will appear as the description proceeds, the invention resides in certain novel features of construction, and in the combination and arrangement of parts as will be hereinafter more fully described and claimed.

In the drawing:—

Figure 1 is a fragmentary inside elevation of the screen sash embodying the features of my invention,

Figure 2 is a sectional view through one rail thereof, and

Figure 3 is a fragmentary detail perspective view of one of the clamping clips.

Referring to the drawing in detail it will be seen that the letters A indicate the four rails of the sash which are secured together in any suitable or preferred manner. These rails are of practically the same construction as far as the essence of the invention is concerned and vary practically only as to their length. A detail description of one of the rails, therefore, will suffice to obtain a clear understanding of all four.

Referring to one of the rails in detail it will be seen that the numeral 5 denotes the outside plate. This rail is formed from a single sheet of metal bent along parallel spaced longitudinal dimensions to form the plate 5 and this plate at one end merges into an overhanging extension 6 in spaced parallelism thereto. At the other edge the plate 5 is extended and bent over upon itself as at 7 and the portion 7 is merged into a plate 8 extending at right angles to the plate 5 and merges into a right angular extending plate 9 which in turn merges into a plate 10 disposed at oblique angles to the plates 9 and 5, and merges into a portion 11 lying flat along a portion of the plate 5 and merging into a portion overlying the portion 6 as is indicated at 12, said portion 12 being ex-

tended around the free edge of the portion 6.

Associated with each rail is a clamp clip C for holding the edges of the foraminous screen sheet 14 in engagement with the rails. 60 Each clip C is formed from a single sheet of material to provide a plate 15, one end of which merges into an acute extension 6 which in turn merges into an obtuse extension 17 extending at an acute angle to the 65 plate 15. The extension 17 merges into an acute extension 18 disposed in spaced parallelism to the plate portion 15 and being disposed between said plate portion 15 and the extension 17. The plate portion 15 is 70 adapted to engage the other surface of the plate 5 while the extension 18 is adapted to engage the surface of the foraminous screen sheet 14.

From the above detailed description it 75 will be seen that the foraminous sheet of screen material may be efficiently attached to the rails of the sash in a reliable manner. The clamp clips are capable of being easily and conveniently engaged with the 80 edges of the screen sheet for holding it in engagement with the rails.

It is thought that the construction, utility, and advantages of this invention will now be apparent to those skilled in this art without a more detailed description thereof. 85

The present embodiment of the invention has been disclosed in detail merely by way of example since in actual practice it attains the features of advantage enumerated as desirable in the statement of the invention and the above description. It will be apparent that changes in the details of construction and in the combination and arrangement of parts may be resorted to without departing from the spirit or scope of the invention as hereinafter claimed or sacrificing any of its advantages. 95

Having thus described the invention, what I claim as new and desire to secure by Letters Patent is:—

In a window screen frame construction, a rail formed from a single sheet of metal bent along spaced parallel longitudinal dimensions to form an inside plate which 105 merges at one edge into an extension, said extension merging into an overhanging extension, said overhanging extension merging into a plate disposed perpendicularly to the first plate, said second plate merging 110 into a third plate extending perpendicularly therefrom, said third plate merging into a

cross plate extending obtusely therefrom and at an acute angle to the first plate and merging into an extension overlying the first plate and bent over upon itself in spaced relation and terminating in a portion forming a pocket with the first mentioned bent over portion, the other edge of the first plate being extended and curved over upon itself to fit in the pocket, and a clamp clip formed 10 from a single sheet of metal bent along par-

allel spaced longitudinal dimensions to form a plate having one edge merging into an acutely disposed extension, said extension of the clip merging into a second extension acutely disposed to the plate of the clip, 15 said second extension of the clip merging into a third extension disposed parallel with the plate of the clip.

In testimony whereof I affix my signature.
OSCAR VENDAL NELSON.
